UNITED STATES PATENT OFFICE.

CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE-BOILER FURNACE.

1,115,280.

Specification of Letters Patent. Patented Oct. 27, 1914.

Application filed December 18, 1911. Serial No. 666,338.

To all whom it may concern:

Be it known that I, CHARLES B. MOORE, a citizen of the United States, residing at Evanston, in the county of Cook and State 5 of Illinois, have invented certain new and useful Improvements in Locomotive-Boiler Furnaces, of which the following is a specification.

My invention relates to improvements in 10 locomotive boiler furnaces and has particular reference to improvements in refractory baffles, deflecting walls, or so-called arches for the fireboxes of locomotive boilers.

The general objects of my invention are to 15 provide a refractory arch, for installation and use in a locomotive boiler firebox, which is equipped with a plurality of arch-supporting tubes; which shall be of light weight and low cost; which can be quickly 20 and easily installed, and which will materially enhance the commingling and admixing of the firebox gases for the purpose of producing substantially perfect combustion in the firebox.

25 A particular feature of my invention resides in a refractory arch body extending substantially from side sheet to side sheet, resting upon the circulating tubes and comprising transverse rows or lines of comparatively heavy supporting bricks alternating with similar rows of comparatively light top or cover bricks whereby a light, substantially imperforate arch may be quickly built up within a locomotive firebox containing a 35 plurality of circulating tubes.

A special object of my invention is to provide a system of constructing refractory arches in the fireboxes of locomotive boilers containing a plurality of circulating tubes, 40 by means of which an arch can be quickly built or installed in any particular locomotive, of such shape, form, dimensions and surface contour that the most economical results in fuel consumption can be attained 45 therein and at the same time the total weight of the arch will be as low as consistent with the necessary strength and durability of the arch.

My invention consists in the several im- 50 provements, the various constructions and the combinations of parts by which the above objects are attained together with others hereinafter appearing, and all as hereinafter set forth and particularly pointed

out in the appended claims, and will be more 55 readily understood by reference to the accompanying drawings, forming a part of this specification, and in which I have illustrated a preferred structure, together with several modified forms of the invention. 60

In said drawings: Figure 1 is a vertical, longitudinal central sectional view of a locomotive firebox equipped with a refractory arch embodying my invention; Fig. 2 is a horizontal, sectional view of the firebox on 65 the line 2-2 of Fig. 1; Fig. 3 is a vertical transverse sectional view on the line 3-3 of Fig. 1; Fig. 4 is a detail transverse sectional view of the firebox and arch on the line 4-4 of Fig. 2; Fig. 5 is a detail transverse sectional view of the firebox and arch on the line 5-5 of Fig. 2; Fig. 6 is a view similar to Fig. 4, but showing a slightly modified structure; Fig. 7 is a perspective view of one of the span or supporting bricks; Fig. 75 8 is a perspective view of one of the cover bricks showing the lower side thereof; and Fig. 9 is a perspective view showing the upper side of one of the cover or top bricks.

My invention is capable of embodiment 80 in different structures occupying various positions in the firebox and, although I have chosen to limit the illustration thereof to so-called front arches my invention is not thus limited.

The particular function of so-called front arches is to baffle or obstruct the direct flow of the firebox gases from the grate to the flues and cause them to flow backward and forward through the length of the firebox 90 and thereby not only retain them in the firebox a sufficient time to accomplish the complete combustion of the fuel before it escapes through the flues, but also to cause the even distribution of the heat of combustion to the 95 whole interior surface of the firebox.

A front arch usually occupies an inclined position in the firebox with its forward end in close proximity to or in abutment with the lower portion of the firebox and may 100 or may not extend from side sheet to side sheet; it usually extends rearwardly to about the center of the firebox so that the gases in passing around the rear end thereof are forced to the rear portion of the firebox and 105 consequently carry or distribute the heat to the rear end of the crown sheet as well as to the forward end thereof.

A locomotive firebox, as illustrated, consists of a flue sheet 2, side sheets 3, 3, a crown sheet 4 and a rear sheet 5, and is positioned within the boiler shell 6. It is provided with 5 a grate 7 at its lower end. Flues 8 lead forward from the flue sheet and the rear sheet contains a fuel door or opening 9. The firebox, as shown, is equipped with four substantially parallel inclined circulating tubes 10, the same extending from the lower portion of the flue sheet upwardly and rearwardly to the rear sheet and serving to increase the circulation of water between the front and rear water legs of the boiler.

15 Besides having the principal function of deflecting the gases in their passage from the grate to the flues, it is desirable that the arch also operates to intermingle or admix the firebox gases thereby preventing 20 stratification of the gases in the firebox and materially assisting in the perfect combination of the elements of combustion. To accomplish this desired end, I so form my arches that they are provided with a plurality of subsidiary gas deflecting surfaces 25 or walls so that as the gases flow upward along the surface of the arch they are deflected downwardly at various angles and are caused to intermix and intermingle in 30 such a manner that the perfect oxidation of the fuel elements is assured. These deflecting walls also serve the purpose of causing the cinders and solid particles of fuel which may be raised or carried up by the 35 draft from the fuel bed to be deflected or thrown back again upon the grate or fuel body.

My arch being light, or formed up of comparatively light individual bricks, soon 40 attains incandescence and thus assists in the ignition of the firebox gases and fuel particles, and I provide many of the individual bricks with comparatively thin ribs or walls for this purpose.

45 The arch, as illustrated, comprises a plurality of transverse rows of supporting bricks *a* alternating with similar rows of top or cover bricks *b*. These rows of bricks extend from side sheet to side sheet and the 50 arch as a whole is arranged in abutment with the flue sheet. The bricks *a* and *b* are made as large as possible consistent with the features that they shall not be too heavy to be handled with ease, and that they shall 55 not be so large but that they may be readily passed through the fuel door. The length of these bricks is determined by the spacing of the tubes 10, the bricks being long enough to rest upon and span the space between two 60 adjacent tubes. I preferably make the supporting bricks *a* substantially rectangular and solid and provide their ends with grooves *a'* which substantially fit the tubes upon which these bricks rest. The ends 65 *a''* of the bricks *a*, above the grooves

a', are beveled or cut-back to prevent these bricks becoming cemented or fused together in the arch. These bricks being of considerable width, rest firmly in position once they have been placed upon the tubes. The 70 arch illustrated contains three rows of the bricks *a* spaced apart and held in spaced relation by two intermediate rows of the cover or top bricks *b*. The bricks *b*, which are preferably much lighter than the bricks 75 *a*, are formed of a thin slab or panel *b'* provided on its under surface with an open box-like projection *b''* thereby providing the underside of the brick with a gas-mixing cavity *b'''*, and thin depending marginal 80 walls *b'''*. The depending walls form abutments which contact with the sides of the bricks *a* and are adapted to retain the bricks *a* in spaced relation upon the tubes.

The construction of the cover bricks *b* 85 with the wall *b''* set in from the outer margin of the slab *b'* provides an opening or groove *b'''* between the walls of adjacent bricks when they are placed in position. This groove or opening *b'''* is somewhat wider 90 than the diameter of the tubes 10 and, as shown in Fig. 4, the whole surface of the tube 10 is exposed to the firebox gases at these points. This is an advantage in this form of construction because the tubes 10 95 assist greatly in the production of steam in the boiler and hence the protection of their surfaces from the heat of the firebox gases tends to reduce their efficiency in this respect.

The construction of arch, as here described, provides a series of transverse subsidiary walls upon the underside of the arch which are formed by the transverse rows of supporting bricks *a*, separated by 105 cavities, which are covered or closed at their upper ends by the top or cover bricks *b*; and in addition the tops of these cavities are provided with a plurality of smaller 110 cavities and depending deflecting walls on account of the peculiar construction of the cover bricks *b*. In an arch of this construction the rows of bricks *a* necessarily stand the brunt of the scouring action of the cinders and solid fuel particles, and the bricks 115 *b* are to quite an extent protected from this action hence the bricks *b* can be thinner and lighter than the bricks *a* and yet be as long lived.

As clearly illustrated in Figs. 4 and 5, 120 the end or outer bricks of the various transverse rows are wedgingly positioned between the outer tubes and the respective side sheets of the firebox and are not only themselves thus securely held in their positions, but they also prevent any lateral movement of the arch, as a whole, or of the tubes in the firebox, such movement when occurring tending to deteriorate or destroy 125 the tubes. However, it will be readily seen 130

that where the tubes are sufficiently strong in themselves to withstand the weight of the arch and the swaying action of the locomotive without detrimental effects, the end 5 bricks may be dispensed with as far as this function is concerned when it is desired to reduce the lateral width of the arch, or certain of these bricks may be omitted in the construction of the arch.

10 In building arches according to my invention, I first place a transverse row of the supporting bricks *a* upon the tubes 10 adjacent to or in abutment with the flue sheet wedging the outer or end bricks of the row 15 between the outer tubes and the side sheets. I then place a second row of these supporting bricks upon the tubes above the first row retaining them in position by means of a transverse row of the cover bricks *b* which 20 rest upon and space these rows of supporting bricks apart. I then complete the arch by adding further rows of the supporting bricks and cover bricks in like manner until the arch is made of sufficient length or 25 height to suit the firebox and locomotive in which it is being installed. It will now be seen that my arch, containing but two brick forms lends itself readily to the installation and maintenance of arches upon a railroad 30 system which is of wide extension; in that it is necessary to carry a stock of but these two forms of bricks at points where it is desired to make necessary repairs or installations. Further, the arch which I have produced is one which can be installed at a 35 minimum expenditure of time and labor as it is built of individual bricks which in themselves can be readily placed in position.

The form of my arch adds very greatly to 40 the efficiency of such structures over that attained by an arch composed only of bricks of the form of solid or supporting bricks *a*. Not only is the arch much lighter in itself and hence less expensive, this being 45 permissible on account of raising the alternate rows of bricks out of the direct path or action of the cinders or fuel particles, but being light it does not tend to deteriorate or destroy the circulating tubes 10 to the 50 same extent that a heavier arch would.

It is sometimes desirable to make the arch 55 of a heavier construction on account of the peculiar action or strength of the draft, in certain locomotives, and to meet this requirement I sometimes make my arch of the form illustrated in Fig. 6 in which the 60 bricks *b* are made much heavier than the preferred form and the end bricks of the transverse rows, which contain the bricks *b*, are preferably of the solid form or supporting 65 bricks *a*. An arch being made of this form, being heavier, contains and carries considerably more heat than the lighter construction and is to a certain extent stronger 70 and more durable, these latter desirable

qualities in this arch being obtained at the expense of the lightness which is usually desired in arches of this construction.

As many modifications of my invention will readily suggest themselves to one skilled in the art, I do not limit my invention to the specific structures herein shown and described. 70

Having thus described my invention, I claim as new and desire to secure by Letters Patent: 75

1. A locomotive boiler firebox having a plurality of arch tubes, in combination with a refractory arch body resting on said tubes, said body comprising a plurality of longitudinally spaced transverse rows of relatively heavy supporting bricks having tube receiving grooves in their ends, which bricks extend between and rest upon said tubes, and relatively light or cover bricks 80 which rest on said supporting bricks and close the spaces between the rows thereof, said cover bricks being provided on their under surfaces with gas-mixing pockets or cavities, substantially as described. 85

2. A locomotive boiler firebox containing arch supporting tubes, in combination with a plurality of spaced apart transverse rows of refractory bricks resting upon and depending between said arch tubes, said 90 bricks having tube receiving grooves at their ends and a plurality of thin walled arch cover bricks resting on said transverse rows of bricks closing the spaces between them and spacing them apart, and each of said 95 cover bricks being provided with a gas-mixing pocket or cavity on its under side, substantially as described. 100

3. A locomotive boiler firebox having a plurality of arch tubes, in combination with a plurality of transverse rows of relatively heavy solid span bricks, said bricks having tube receiving grooves or sockets at their ends and said bricks being supported by and depending from and between said arch tubes, and a plurality of cover bricks in turn supported by said span bricks and closing the openings between the rows thereof from side to side of the firebox, said cover bricks each being provided with a depending portion adapted to engage the span bricks and hold them in spaced relation, longitudinally in the firebox, said depending portion having a downwardly opening gas-mixing cavity of relatively large area, substantially as 110 described. 115

4. A locomotive boiler firebox containing a plurality of inclined, substantially parallel arch tubes, in combination with two or more transverse rows of relatively heavy refractory bricks longitudinally spaced apart upon said tubes and abutting the sides of the firebox, each brick of said rows depending below the upper surface of said tubes and being held thereby against movement trans- 120 125

- versely in the firebox and a plurality of relatively light cover bricks closing the spaces between said rows, each of said cover bricks being supported by two said rows and each 5 having a gas-mixing cavity of relatively large area in its lower side, substantially as described.
5. A locomotive boiler firebox containing a plurality of inclined arch tubes, in combination with two or more transverse rows of refractory bricks supported by said tubes and abutting the side sheets of the firebox and spaced apart at different heights on said tubes, each said row comprising bricks having 10 tube fitting and engaging grooves at their ends and a plurality of relatively light refractory cavitied bricks supported at their ends by adjacent transverse rows of refractory bricks and closing the spaces 15 between said rows from side sheet to side sheet of the firebox, substantially as described.
6. A locomotive boiler firebox containing arch tubes, in combination with two or more 20 rows of relatively heavy refractory bricks arranged transversely therein supported by and spaced apart upon said tubes, the individual bricks of said rows having tube receiving and engaging grooves at their ends, 25 in combination with refractory cavitied bricks resting upon and connecting said rows, extending downwardly therebetween and forming therewith an arch containing 30 one or more transverse closed topped recesses or pockets, each thereof having a plurality of subsidiary pockets in its top, 35 substantially as described.
7. A locomotive boiler firebox containing arch tubes, in combination with an arch 40 comprising a plurality of rows of refractory bricks, each row being composed of several bricks having their ends in engaging abutment with said tubes, said rows being spaced apart on said tubes, and a substantially imperforate cavity containing refractory covering resting upon each of the 45 adjacent pairs of said rows laterally co-extensive therewith and providing the arch with a plurality of top closed transversely 50 extending recesses, each of said recesses being provided with a plurality of gas-mixing cavities in its upper end, substantially as described.
8. A locomotive boiler firebox containing 55 a plurality of inclined parallel arch-supporting water tubes, in combination with a plurality of parallel spans, each composed of several refractory bricks arranged end-to-end and resting transversely upon said tubes, said spans being spaced apart upon 60 said tubes, and rows of cover bricks intermediate said spans, each of said cover bricks being provided with a depending inner portion 65 having a downwardly opening gas-mixing pocket therein of relatively large

area, said cover bricks resting upon and spacing apart said span bricks and exposing the tubes between the spans to the action of the gases of combustion, substantially as described.

9. A locomotive boiler firebox, in combination with a plurality of inclined arch tubes therein, refractory spans disposed upon said tubes and spaced apart longitudinally thereon, each said span comprising a number of separate bricks of lengths substantially corresponding to the spacing of said tubes and having tube receiving and engaging grooves at their ends and refractory arch cover bricks spanning the space between resting upon and spacing apart said spans, each of said cover bricks being provided with a shallow, gas-mixing pocket or cavity in its lower side.

10. In a locomotive firebox, a plurality of parallel arch tubes extending longitudinally in the firebox, in combination with longitudinal parallel rows of firebricks in said firebox, each row resting upon a pair of adjacent tubes, the bricks thereof being socketed at their ends to engage said tubes, said rows lying adjacent to each other and the adjacent ends of the bricks in said adjacent rows engaging the same tube, said bricks in each row being spaced apart longitudinally, and cavitied cover bricks with flanges thereon resting upon and spacing apart the first said bricks.

11. In a locomotive firebox, a plurality of parallel arch tubes extending longitudinally in the firebox, in combination with socketed supporting bricks resting upon and engaging said tubes by means of the sockets on said bricks, and thin spacing cover bricks resting upon and spacing said socketed bricks apart, said cover bricks each having a depending marginal rib or web spaced inward from the edge thereof forming supporting or spacing shoulders at the longitudinal ends, said rib or shoulder at the side toward the tube being spaced inward from the tube.

12. A locomotive boiler firebox having a plurality of arch tubes, in combination with a refractory arch body resting on said tubes, said body comprising a plurality of longitudinally spaced transverse rows of supporting bricks resting upon and depending between said tubes and cover bricks raised above said tubes and resting upon and partly between said supporting bricks, forming an arch having transverse grooves or channels on its underside, said cover bricks having a depending closed sided portion forming an open bottomed downwardly facing shallow cavity or pit.

13. A locomotive boiler firebox having a plurality of inclined parallel water-circulating tubes extending from the lower front end of the firebox to the upper rear end

thereof, in combination with alternate transverse rows of relatively massive firebricks, said bricks being of substantially rectangular shape and solid and having transverse 5 sockets or grooves on their lower end corners adapted to fit upon said tubes for supporting said bricks at each end and relatively light thin firebricks resting along their edges on said massive bricks and each 10 having a depending hollow member formed with opposing shoulders to space the rows

of massive bricks apart and having a downwardly opening gas-mixing pocket therein.

In testimony whereof, I have hereunto set my hand, this 5th day of December, 15 1911, in the presence of two subscribing witnesses.

CHARLES B. MOORE.
